DISPENSER CAP FOR A PRESSURIZED CONTAINER

Jimmie L. Mason, Hacienda Heights, and Howard Clyde Tracy, Jr., Los Angeles, Calif., assignors to Dart Industries Inc., Los Angeles, Calif.

Filed Apr. 3, 1970, Ser. No. 22,234

Term of patent 14 years

Int. Cl. D9—07
U.S. Cl. D9—258

FIG. 1

FIG. 3

FIG. 2

FIG. 4

FIG. 5

FIG. 6

FIG. 1 is a perspective view of a dispenser cap for a pressurized container embodying our new design;

FIG. 2 is a top plan view thereof;

FIG. 3 is a side elevation view thereof;

FIG. 4 is an elevation view looking from the right of FIG. 3;

FIG. 5 is an elevation view looking from the left of FIG. 3; and

FIG. 6 is a bottom plan view thereof.

We claim:

The ornamental design for a dispenser cap for a pressurized container, substantially as shown.
